TRANSMITTING MEASUREMENTS TO A
REMOTE POINT

Fritz Fischer and Hans Schuchmann, Berlin-Charlottenburg, Germany, assignors to Siemens & Halske, Aktiengesellschaft, Siemensstadt, near Berlin, Germany, a corporation of Germany

Application July 24, 1929, Serial No. 380,532
In Germany July 25, 1928

11 Claims. (Cl. 177—351)

Our invention relates to improvements in transmitting measurements to a remote point.

Briefly stated, our invention comprises transmitting measured values or magnitudes to a remote station by means of a comparatively small number of signs, and to this end the value to be transmitted is first automatically divided into a number of terms whose sum is equal to, or very approximately equal to, such value, and these terms are transmitted to the distant station. Each measured value is thus expressed as one or as the sum of two or more of these terms. The terms themselves comprise a group of arbitrarily selected number values. At the receiving station these received terms may be indicated individually, or they may be automatically added together so that the measured value may be read off directly. Our invention can also be employed to transmit information other than measured values provided that such information can be converted into one or a plurality of comparison values for transmission; and accordingly we are able by means of our invention to transmit to a distant station the condition of a switch, or the phase relation of two alternating lines.

Stated more fully, according to our improved method, the value of the magnitude to be transmitted may be expressed in terms of a group of arbitrarily selected numbers, for instance, as a sum of powers of the number two, and by means of signals of any suitable kind of each power of two there is reported to the receiver station whether this power of two is contained in the thus measured value or not. In order to enable those powers of two to be determined which are contained in the value to be transmitted, it may first be determined by way of test whether the highest power of two (or the highest number of the group of numbers employed as the comparison values) is contained in the value to be transmitted, then whether the next smaller power of two (i. e. the second highest number of the groups of comparison numbers) is contained in the balance, and so on. The distance to be traversed is immaterial so far as our improved method is concerned. The remote transmission may take place between substations and main stations or from a point accessible with difficulty or not easily supervisable for other reasons, to a point where the indicating instrument may be watched more easily. Instead of a single indicating instrument a plurality of them may be provided which give the same indications at a number of different points, for instance to attendants as well as in the control office. Signals

of any kind, such as impulse combinations, may be employed for transmitting the signals.

In a method of transmission as described above, it is of course desirable that a measured value be transmitted to a remote receiving station with a minimum of signals. We have found that if a value is transmitted in terms of the powers of 2, the exact values or very close approximations thereof can be transmitted with very few signals; but, of course, other combinations of comparison numbers or values may be employed.

The transmission of measured values by combinations of impulses to an indicating instrument comprises two fundamental problems. The first consists in the necessity of translating the measuring value for the transmission, and the second consists in translating the signs arriving at the receiving station again into a value capable of being indicated. Both problems may be carried out by similar means. The translation of a measured amount may according to our invention, for instance, take place in the following manner:

The measured value to be transmitted, for instance a current, is measured by a suitable measuring instrument, such as an ammeter. The torque exerted upon the spindle of the ammeter is a measure of the strength of the current.

According to our invention the torque set up by the current is compensated by a sum of individual torques stepped in powers of two in such a manner that a pointer mounted on the revolving spindle of the measuring instrument stands, after the compensation, in the zero position. For this purpose a device engages the spindle of the measuring instrument by means of which individual torques of different magnitude may be consecutively transmitted to the revolving spindle until the torque exerted by the current is counteracted. This may, for instance, be effected by connecting the spindle of the measuring instrument rigidly with the spindle of a moving coil instrument and by increasing the current in the moving coil to such a total value that the moving coil system develops a torque which is exactly as great as the torque developed by the measuring instrument but of opposite direction. The compensation of the torque of the measuring instrument may also be effected mechanically by rendering a series of springs of different strengths operative on the spindle of the measuring instrument. Inasmuch as the individual torques are so stepped that their values stand in the relation of the powers of two,

different total torques may be composed from six of such stepped individual comparison torques, in this way it is possible to transmit a scale of 120 division lines with such a degree of accuracy that the adjustment of the pointer of the indicating instrument at the receiving station deviates from the accurately measured value by not more than one division line on the scale. To each of the effective individual comparison torques there corresponds an impulse which is transmitted to the receiving instrument. The accuracy of the transmission is extremely great and for the transmission of 64 measured values there are required only 6 relays if the individual torques are released in the simplest manner by a relay each. The excitation of the relay may, for instance, be controlled by electric, pneumatic or other impulses which are sent across the transmission line or by any other suitable devices mounted at the measuring station.

The second problem to be solved in the remote transmission consists, as already mentioned, in the fact that at the receiving apparatus the arriving impulses must be utilized to adjust the pointer of the indicating instrument. In reversing the method already described for the translation of the measuring value into impulses, relays are energized at the receiver which may, for instance, be a voltmeter or ammeter of standard design, in correspondence with the arriving impulses. These relays are capable of varying the deflection of the pointer of the indicating instrument by connecting in circuit resistances connected in series or parallel. Instead of an electric indicating instrument a measuring device may, of course, be used in which individual torques of different values are mechanically transmitted by the arriving impulses to the spindle of the indicating instrument which also stands under the action of a control force, such as a spring force, and which adjusts itself so that the sum of the individual torques is equal to the torque of the control force.

It will be understood that it is immaterial for our invention in what manner the torques for the compensation of the torque of the measuring instrument at the transmitting station and the torques for adjusting the indicating instrument are produced. They may be produced not only electrically and mechanically, but also pneumatically. Means of different nature may be employed at the transmitting and receiving stations. Further details of our invention will appear as the description proceeds with reference to the drawings affixed to our specification and illustrating a preferred embodiment of our invention.

In said drawings,

Fig. 1 is a diagrammatic view illustrating mechanism for compensating the torque of the measuring instrument;

Fig. 2 is a view taken along the line 2—2 of Fig. 1 looking in the direction of the arrow;

Fig. 3 shows the mechanism which controls the relays of Fig. 1 for compensating the torque of the measuring instrument and illustrates the wiring diagram for such relays;

Fig. 4 is a diagrammatic view illustrating a form of receiving apparatus for translating the received current impulses to an indicating instrument;

Fig. 5 shows an arrangement for repeating the impulses transmitted so as to avoid the possibility of error;

Fig. 6 shows a central station and a plurality

of sub-stations connected therewith by one outgoing and one return line;

Fig. 7 shows diagrammatically a modified form of the invention; and

Fig. 8 shows an arrangement for interconnecting two alternating current networks.

In order to simplify the illustration the system shown possesses only three relays by the aid of which three individual torques may be controlled. From three individual torques may be composed 10 eight different total torques.

The compensation of the measuring instrument is shown in Fig. 1 wherein the measuring instrument is shown as a moving coil instrument 1 with the permanent magnet 2 and the pointer 15 4 mounted on the spindle of the revolving system. On the spindle of the measuring instrument there is mounted a bow or loop 5 which extends under three helical springs 6, 7, 8 (Fig. 2), the free ends of which are normally held in their upper position by the three pushrods 9, 10, 11. These push rods are engaged by the spring-pressed armatures of relays 12, 13, and 14, and when the relays are deenergized, the rods 9, 10, 11 are raised by the respective armatures, so as to prevent the springs 6, 7, 8 from pressing on the bow 5. When however one of the relays 12, 13, 14 is excited, its armature will allow the push rod 9, 10, or 11 respectively to drop under the influence of gravity and of the corresponding spring 6, 7, or 8 respectively, so that this spring will press down on the bow 5. The spiral springs 6, 7, 8 are at their other ends secured to the outer circumference of a stationary bushing 15 in which is journaled the spindle 3 of the measuring instrument. The strength of the springs 6, 7, 8 shown in Fig. 2, is stepped in such a manner that their powers stand in the ratio of 2:4:8, as indicated by the relation of the thicknesses of these springs in said figure. The value measured by the moving coil instrument, such as a current, develops a torque which tends to turn the pointer 4 and therewith the bow 5 clockwise. The springs 6, 7, 8 on the other hand press on the bow 5 in such a manner that they tend to turn the spindle of the system and therewith also the pointer 4 counterclockwise. Which of the springs 6, 7 and 8 is operative depends upon which of the relays 12, 13, 14 has responded. The choice between the springs 6, 7 and 8 is, as described hereinbelow made so that the torque of the measuring instrument caused by the current is compensated. The pointer 4 is adapted to set itself over two contact pieces 17 and 18 located below the path of the pointer and insulated one from the other as indicated at 16. A drop bow 19 forces the pointer 4 from time to time down and on to its support, for instance through the action of an electromagnet 20 energized periodically in any well-known or approved manner. According to whether the pointer is forced down upon the contact 17 or 18 a current of positive or negative direction flows across the pointer from a source such as, for instance, the battery B shown in Fig. 3, the wires 500, 501 leading from the contacts 17 and 18 respectively to opposite poles of said battery.

The compensation of the measuring instrument takes place in such a way that by means of a contact device the relays 12, 13, 14 are energized in succession and in the sequence stated so that first the greatest individual countertorque becomes operative on the bow 5, then the next smaller and so on.

By means of a special device, one form of which is shown in Fig. 3, and the contacts 17 and 18

which are selectively closed by the pointer 4, provision is now made that all relays are excited once but that at the end of the compensation only those relays remain switched in whose sum just suffices for the compensation of the torque of the measuring instruments. The device for exciting the relays 12, 13, 14 in Fig. 3 possesses an insulating base plate 30 upon which are located two rings 31 and 32 insulated one from the other and composed of conducting material, the rings moving together with the disc 30 in the direction indicated by the arrow. The ring 31 is connected to the positive pole of a source of current (not shown) through a sliding contact 37 and a wire 502, the ring 32 is likewise connected to such positive pole through a sliding contact 38, and wires 503, 502 if an armature 35 is brought against a contact 35' by the proper energizing of a polarized relay 34. One terminal of said relay is connected by a wire 504 with the midpoint of the battery B, while the other terminal is connected by a wire 505 with the pointer 4. When the relay 34 is energized in the opposite direction, the armature 35 is removed from the contact 35' and brought against a stop 35''. The relay 34 is excited through the pointer 4 (Fig. 1) in one or the other direction according to whether the pointer touches the contact piece 17 or 18. The ring 31 touches during its rotation by means of a projecting vane 33 in succession the stationary contacts 121, 131, 141 which are electrically connected with one end of the windings of the relays 12, 13, 14 and thus connects them momentarily to the positive pole of the source of current indicated by the + sign at the left-hand end of the wire 502. The other ends of all the relay windings are permanently connected to the negative pole terminal of this source of current. The relays 12, 13, 14 are momentarily excited and allow the free ends of the spiral springs 6, 7, 8 to drop on the bow 5 of the measuring instrument since the push rods 9, 10, 11 (Fig. 1) move downwards by way of test. If the first countertorque exerted by the spring 8 when the latter is released by the relay 12 does not suffice to compensate the torque of the measuring instrument the pointer 4 is forced on to the contact 18 of its support by the drop bow 19. In this way the polarized relay 34 (Fig. 3) is excited which, by means of its armature 35, then connects the ring 32 to the source of current. When the relay 12 was energized by the aid of the vane 33 it had connected an armature 122 in a holding circuit for the relay 12 passing through a contact 123 and the ring 31. When shortly afterwards the vane 33 leaves the contact 121 a vane 36 secured to the ring 32 touches the contact 123. At this moment the relay 34 is excited because the torque of the spring 8 has not sufficed to turn the pointer 4 back into its zero position over the contact 17; the positive pole of the exciter source of current for the relay 12 is electrically connected through the closed armature 122, the ring 32, vane 36 and contact 123 to one end of the winding of the relay 12. Relay 12 remains excited first through the vane 36 and armature 35 and then when the disc 30 is advanced again through the ring 31. During the further progress the relay 13 is rendered operative exactly as described with reference to the relay 12 and in case the power of the springs 7 and 8 together is not strong enough to compensate the torque of the measuring instrument the relay 13 also remains in circuit and both springs 7 and 8 remain operative on the spindle of the measuring instrument. If it is now assumed that by the springs 7 and 8 the compensation of the measuring instrument has already been attained to such an extent that by the addition of the countertorque exerted by the spring 6 the sum of the individual countertorques is greater than the torque of the measuring instrument, the pointer 4 of the measuring instrument will be pressed on the contact 17 of its support after the relay 14 has been excited. The relay 34 is then excited in such a manner that its armature 35 comes against the upper stop 35'' and the holding circuit for the relay 14 is broken when the vane 36 reaches the contact 143. The compensation is thus effected by the individual countertorques rendered operative by the relays 12 and 13. The relays 12 and 13 are excited. As follows from the described mode of operation, the drop bow 19 (Fig. 1) must cooperate with the contact device illustrated in Fig. 3 in such a manner that it depresses the pointer 4 at the moments in which the vane or blade 36 just touches the contacts 123, 133, or 143. Every time a relay is excited by way of test to render the countertorque exerted by the particular spring which such relay has released, operative on the spindle of the instrument, the pointer 4 is freely movable and sets itself anew over the contacts 17, 18.

For the transmission to the receiving instrument a contact device is then used which for each relay 12, 13, 14 connected in circuit sends a current impulse across the remote transmission line and at the receiving station accurately corresponding relays are excited by the adjustment 35 of the indicating instrument by a synchronous contacting device. It is, of course, also possible to send a current impulse for each non-excited relay 12, 13, 14 to the receiver station, each impulse causing at the receiving station the de- 40 excitation of a corresponding relay or the reduction of the sum of individual countertorques acting on the axle of the indicating instrument. The exciter circuits for the receiver station can be passed across contacts 124, 134, 144 (Figs. 1 45 and 3) controlled by the relays 12, 13, 14, and the remote transmission line. Each contact 124, 134, 144 is permanently connected with one pole of a source of electricity (not shown), for instance the negative pole, as indicated in Fig. 3, 50 and when closed upon the energizing of one of the relays 12, 13, or 14, the corresponding contact 124, 134, or 144 respectively will, through a corresponding line wire 506, 507 or 508 respectively, cause an energizing current to flow 55 through one of the relays 61, 62, or 63 respectively located at the receiving station. One terminal of each relay 61, 62, 63 is connected with the other pole of said source of electricity, the other terminal being connected with the respective line wires 506, 507, 508. Those relays will then be excited at the receiving station the exciter circuit of which is closed at the transmitter station. At the receiving station an indicating instrument may be provided, as already mentioned, 60 on the spindle of which two opposite torques are adapted to act. One of the torques is, for instance, produced by spring power, while the other countertorque is composed of a sum of individual torques exactly as at the transmitting station. 65

The operation of the apparatus shown in Figs. 1-3 is as follows:

It is assumed that a current flows through the armature of the measuring instrument, the magnitude of which current is to be measured in 75

- terms of the arbitrarily selected number values for transmission to the remote station. A torque acts on the armature of the instrument, which torque is proportional to the current strength.
- 5 According to the invention the value of this torque is broken up into a number of terms whose sum is equal to or closely approximates such value. This is accomplished by means of the relays 12, 13 and 14 and the springs 6, 7 and 8.
- 10 The strength of the springs corresponds to the magnitudes of the comparison terms or values. With the aid of the relays, the ends of the springs are shifted by a certain amount so that a counter-torque corresponding to this amount is exerted
- 15 upon the armature of the measuring instrument.
- The rotating rings 31 and 32 excite the relays 12, 13 and 14 in succession. In this way there is impressed upon the armature of the instrument 1 a series of counter-torques in the same order.
- 20 The relay 12 is first excited and consequently the greatest unit counter-torque exerted. If this counter-torque is greater than that exerted by the current being measured, the pointer 4 is rotated counter-clockwise against the contact 17,
- 25 the circuit of the relay 34 being thereby closed in such manner that the switch 35 opens its contact. When the vanes 33 and 36 slide over contacts 121 and 123, the holding circuit of the relay 12 is broken and its armature falls. After
- 30 the relay 12, the relay 13 is excited across the vane 33. We shall assume that the counter-torque exerted by the spring released by relay 13 is smaller than that exerted by the current being measured. In such case, the circuit of relay 34
- 35 is closed across the pointer 4 in such manner that the switch 35 closes its contact. As a result, the ring 32 is placed in circuit with the battery, so that the holding circuit of the relay 13 remains closed through the vane 36 even when the vanes
- 40 33 and 36 pass the contacts 133 and 131. The relay 13 thus remains excited. The same order of events occurs with relay 14.
- Only three relays are shown in the drawings, but a larger number may obviously be employed.
- 45 The larger the number of relays, the closer the approximation. After the trial tests have been made with all of the relays, those which are excited are a measure of the current strength.
- The mode of operation of an electric receiving
- 50 instrument is illustrated by way of example in Fig. 4. The indicating instrument is a voltmeter V. The voltage is measured at a series connection of resistances 54, 55, 56. There are also provided three further resistances 51, 52, 53 of such value that the resistances 51 and 54, 52 and 55 as well as 53 and 56 are in pairs equal. The resistances of the first pair are so related in magnitude to those of the second and of the third pair that the magnitudes of the resistances of different pairs will be in the ratio of 2:4:8. The resistances are controlled by relays 61, 62 and 63 by means of the relay armatures 611, 612, 621, 622, 631, 632. The relays 61, 62 and 63 are the receiver relays and the relay 61 is excited if at
- 55 the transmitting station the relay 12 is excited. Relay 62 belongs in the same manner to relay 13 at the transmitting station and relay 63 correspondingly to relay 14. In order that the current which traverses the resistances from 51 to
- 60 56 in series connection should not change its value when the receiver relays respond, the connection is such that the sum of the resistances 51-56 remains unchanged. For this purpose the relays 61, 62, 63 always short circuit by their
- 65 armatures 611, 621, 631 and 612, 622, 632 one of

the resistances 51, 52 and 53 when they switch into circuit one of the corresponding resistances 54, 55 and 56 and vice versa, the resistances 54, 55, and 56 being equal in magnitude to the resistances 51, 52, and 53 respectively. In order that the indications of the indicating instrument V may be independent of fluctuations of the voltage connected to the series connection of the resistances, it is advisable to employ as indicating instrument a quotient instrument, for instance 10 a cross-coil instrument.

The reliability of the transmission may further be increased by special means. In the transmission of the impulse combinations from the transmitting to the receiving station faults may 15 be caused by some impulses dispatched from the transmitting station not arriving at the receiving station or by voltages impressed upon the transmission lines from any external source. As far as such faults occur accidentally and temporarily 20 they can not always be directly recognized. The correct transmission may in spite of this be effectively protected by repeating every impulse dispatched from the transmitting station. Each impulse may, for instance, be repeated three 25 times and provisions may be made at the receiving station that each of the receiving relays (61, 62, 63) becomes excited then only if all three impulses or at least two impulses arrive in coincidence. The arrangement may be such that 30 from the transmitting station each impulse consists of two impulses of opposite direction, for instance of a positive and a negative current impulse or vice versa. At the receiving station each current impulse then closes one or the other 35 of two alternating contacts by means of a polarized relay each, the arrangement being such that only if all arriving signs consist of two opposite current impulses can the receiving instrument at the receiving station be adjusted. 40 A receiving connection which operates in this manner is by way of example illustrated in Fig. 5 of the drawings.

In the system illustrated in Fig. 5, an indicating instrument V is selected and adjusted by 45 means of a contact device 100 in correspondence with the impulses arriving through the entrance relay 101. For this purpose the contact device 100 is provided with a contact arm 102 which carries three contact pieces 103, 104 and 105 insulated one from the other. The contact 105 is connected to the positive terminal of the local battery and slides during the major part of its revolution on a contact bar 106. The contact piece 104 slides over contacts 107' and 201 to 50 206 and the contact piece 103 over contacts 301 to 306. With the contacts 201 to 206 are connected the relays 211, 221 and so on up to 261. The relays 211, 221, 231 serve for the adjustment and the relays 241, 251 and 261 for the selection 60 of the indicating instrument V. The contact arm 102 revolves contraclockwise. If in the shown inoperative position of the contact arm the contact 104 is connected by the polarized relay 101 to the positive pole of the local battery a 65 starting relay 107 connected with the contact 107' by a wire 107'' is excited thereby which releases the contact arm 102 so that it may revolve. At the transmitting station there moves forward from the same moment a contact arm with the 70 same speed, the arms being thus synchronized so that at the moments when the contact arm 102 touches its contacts at the receiving station the relay 101 can be excited across corresponding contacts at the transmitting station. Each of 75

- the relays 211, 221 and 231 becomes excited when the positive pole of the local battery is connected by the contact 104 and the armature of the relay 101 to the respective contact 201, 202 or 203.
- 5 The relays 211, 221 and 231 each close by their armatures 211a, 221a, 231a a holding circuit which is closed from the minus pole of the local battery by the respective relay winding, the armature of each excited relay, line 110, the contact bar 106 and the contact 105 of the contact arm 102 to positive terminal of the local battery, according to which of the transmitting relays 12, 13, 14 (Fig. 1) is connected in circuit for the compensation of the measuring instrument 1 if the polarized entrance relay 101 at the receiving station is excited in one or the other direction. For this purpose the relay contacts 124, 134 and 144 are, in contrast with the illustration in Fig. 1, so designed that when their 10 relays are excited they close a connection to the positive pole of the local battery and when not excited to the negative pole. The arrangement at the transmitting station is such that for each relay 12, 13, 14 which remains in circuit an impulse combination consisting of a positive and a subsequent negative current surge is dispatched across the remote line to the relay 101. For each of the relays 12, 13, 14 which is not excited a negative and then a positive current surge is transmitted. At the receiving station these arriving current surges have the effect that the contacts 301, 302 or 303, 304, or 305, 306 first receive positive and then negative potential or vice versa in pairs across the contact 103 of the contact arm 102. In this way the relays 301a, 302a, 303a and so on up to 306a connected to these contacts are excited by a positive or a negative impulse.
- If all the impulses have been properly transmitted the armatures of the relays 301b to 306b are in pairs placed against their outer or inner back contacts so that a closed circuit from the armature 301b to the armature 306b is set up. If one of the impulses to be transmitted does not arrive or if it receives a wrong direction due to external influences in the transmission line or if a permanent current is superimposed over the impulses due to an insulation fault or the action of adjacent circuits, the circuit remains open at least at one of the said armatures 301b to 306b. This has the effect that no indicating instrument is selected at the receiving station in which the impulse combination arriving could cause an indication.
- 55 The selection of the indicating instrument V is carried out by the contact arm 102 on the second half of its path. When it sweeps past the contacts 204, 205 and 206 the exciter windings of the selector relays 241, 251 and 261 are connected to the armature of the receiving relay 101 and those of the three selector relays which through the armature of the receiver relay 101 are connected to the positive terminal of the local battery become excited. Exactly like the relays 211, 221 and 231, each excited selector relay connects itself by means of its armature 241a, 251a or 261a in a holding circuit which passes over the line 110, the contact bar 106 and the contact 105 of the contact arm 102 to the positive pole of the local battery. To the selector relays 241, 251 and 261 are coordinated, respectively, contacts 241b, 251b and 251c, and 261b to 261e. For the adjustment of the indicator instrument V it is necessary to excite a relay R. For this purpose the 70 relays 241 and 261 must be excited by the selector relays and the relay 251 must remain unexcited. The relay R is then located in a closed circuit which, starting from the negative pole of the local battery, is carried back to the positive pole of the local battery across the winding of the relay R, the attracted armature 261c, the armature 251b resting upon its lower contact, the attracted armature 241b and across the series contacts 306b to 301b. The relay R cannot be excited if the series connection of the contacts 301b to 306b contains a gap. It is not necessary that the relays 301a, 302a and so on should be excited in the sequence illustrated in Fig. 5 by way of example. The excitation may, for instance, start with the relays 301a, 303a and so on and then 15 the relays 302a, 304a and so on may be excited. The arrangement shown in Fig. 5 may also be changed in such a manner that the entrance relay 101 does not receive impulses in both directions but in one direction only. The combination of signs then consists of current signs and intervals. At the armature of the entrance relay 101 a spring is then provided which pulls the armature down on one of its back contacts during each interval in the current. 25
- The relay R cooperates with the relays 211, 221 and 231 in order to effect the adjustment of the indicating instrument V. It should be added that the relays 211, 221 and 231 control an armature 211b, 221b and 231b, respectively. Those of the 30 relays 211, 221 and 231 which have previously closed a holding circuit for themselves hold their armatures 211b, 221b and 231b attracted and thus connected with the positive pole of the local battery. The relay R now controls double armatures 35 R₁₁, R₁₂, R₂₁, R₂₂, R₃₁, R₃₂. As long as the relay R is not excited the armatures R₁₂, R₂₂ and R₃₂ are connected to the positive pole of the local battery. The armatures R₁₁, R₂₁ and R₃₁ are connected with the before mentioned armatures 40 211b, 221b and 231b if the relay R is excited while at the same time the relay armatures R₁₂, R₂₂ and R₃₂ are released from their connection to the positive pole. With the armatures R₁₂, R₂₂ and R₃₂ are connected the adjusting relays 61, 62 and 45 63 also referred to above in connection with Fig. 4, which on excitation simultaneously attract the armatures 611, 612 or 621, 622 or 631, 632. In addition to these armatures, the said adjusting relays also each possess an armature 610, 620 and 50 630 respectively adapted to close a holding circuit after the respective adjusting relay has been energized. The relays 61, 62, 63 are constructed in such a manner that their armatures 610, 620, 630 respectively will be delayed in their leaving the 55 respective contacts. For this purpose, the construction is such that when the armatures R₁₁, R₁₂, or R₂₁, R₂₂, or R₃₁, R₃₂ leave their contacts, the armatures 610, 620 or 630 respectively will keep their respective contacts closed until the 60 armatures R₁₂, R₂₂, or R₃₂ engage their respective contacts. In this manner a holding circuit is established for any one of the relays 61, 62, or 63 which has been excited over the armature R₁₁, R₂₁, or R₃₁ and one of the armatures 211b, 221b, 65 or 231b respectively. According as the relay 211, 221, or 231 is energized, the corresponding adjusting relay 61, 62, or 63 will also be energized. As has been explained above, whether the relay 211, 221, or 231 is energized, depends on the condition 70 of the relays 12, 13, or 14 respectively at the transmitting station. In this way the adjustment of the relays 12, 13, 14 at the transmitting station is by means of the relays 211, 221, 231 transmitted to the relays 61, 62 and 63 because 75

of these latter only such can be excited when the relay R responds and place themselves in a holding circuit which find a closed circuit through one of the armatures 211b and 221b and 231b as well as across the armatures R1, R2 or R3 and one of the armatures 610, 620, 630.

As shown by way of example in Fig. 6 it is possible by one outgoing line and one return line to select various substations N₁, N₂, N₃ from one central station Z by dispatching impulse combinations from the main station for the selection of a substation or a measuring instrument M₁, M₂, M₃, each substation to be selected or each measuring instrument in such a station having a definite combination apportioned to it. At the substation the compensation of the measuring instrument provided may commence after the selection of a measuring station and after the compensation has been effected it can then in the manner described be reported to the receiving station which individual torques were needed for the compensation at the measuring station. The selection can take place in the same manner as the selection of the measuring instrument V of the arrangement illustrated in Fig. 5. As in Fig. 5, the relays are excited only when the relays 241, 251 and 261 are excited in a definite combination; thus there can be excited, from the receiving station Z, a relay in one of the substations N₁ to N₃ which sets into motion the compensating device illustrated in Figs. 1 to 3. At the end of a revolution of the contact elements 31, 32 (Fig. 3), the transmission of the torques necessary to effect the compensation can be automatically released. The arrangement may, however, also be such that at each substation the compensation of the measuring instrument is repeated in regular intervals, for instance by a clockwork. The order for starting the contact device at the main station and the substation is then preferably given by the substation. The individual procedures of the selection and the transmission of a measurement result may preferably be so interconnected, that while from the main station a substation and a measuring instrument in that station are chosen, the compensation takes place at another station which is transmitted only when the impulses sent by the main station for the selection are finished.

In order to obtain accurate transmission, it is advantageous to control the synchronously rotating contact arms in the sending and receiving stations from that station which transmits the communication, as has already been mentioned. In the contact mechanism 701, 702 of the main or receiving station Z illustrated in Fig. 6, there is shown a magnet 703 which is operative to attract an armature 704 and in this manner to withdraw a braking or latch member 705. By such operation, the disk 706 is released, so that the contact device 702 is able to rotate. The impulse by which the magnet 703 is excited is the starting impulse. As all the sub-stations N₁ to N₃ are connected by conductors in the receiving station, this starting impulse can be sent from each of these stations. In this way it is made certain that the switch mechanism in the receiving station Z runs synchronously with the contact arm in the sub-station which transmits the communication.

The process described up to now requires a considerable time until the pointer of the measuring instrument has set itself anew. Although

the relays controlling the compensation torques require extremely little time for their response, this remote transmission is nevertheless too slow and sluggish for many engineering purposes because after the addition of a further individual torque it is necessary to wait to determine which position the pointer of the instrument takes up. The modification of our invention which will be described now enables a quicker transmission of a pointer position or a measured value. This equipment is thus also suitable for protective connections such, as those for instance, in which the current or the output is measured at different points of a plant and compared with one another.

In another modification of our invention the value to be transmitted connects a transmitter resistance into a bridge connection and an automatic device sets up balance again by connecting in circuit or cutting out a number of individual resistances and in this way causes the dispatch of a definite signal or a definite combination of signals. The measuring instrument may be any suitable instrument the pointer of which controls a resistance. Preferably the pointer is periodically depressed by a drop bow and in this way connects greater or smaller resistances into a bridge connection. For setting up again the bridge balance which has been disturbed in this manner the individual resistances from the largest down to the smallest are in succession switched into circuit or short-circuited in any suitable manner, for instance by a revolving contact device. After each addition or subtraction of an individual resistance a polarized relay in a diagonal branch of the bridge by closing one or the other of its armature contacts indicates whether the last resistance was too great or not great enough for producing the state of balance in the bridge connection. In the first case the switching operation is cancelled again, while in the second case the last added or subtracted individual resistance is blocked in its connection by the armature contact of the polarized bridge relay. The same procedures are repeated at the next smaller individual resistance. The bridge relay adjusts itself much more quickly than a measuring instrument. The pointer of the transmitting instrument on the other hand is detained on the bridge resistance by the drop bow only until the balancing of the bridge as well as the remote signalling over the individual resistances required for the balancing are finished. The drop bow is coupled with the contact device in such a manner that both cooperate correctly as regards time.

Apart from the advantage already mentioned that the remote transmission of a measured value takes place more quickly, i. e. that the resetting movements of the indicating instrument at the receiving station can follow each other at short intervals, our invention has still other great advantages. In the first place, any desired measuring instrument may now be used as transmitter instrument. Also, since the pointer of the transmitter measuring instrument is able to adjust itself freely, measuring instruments with very weak directional forces may be used. The readings of the measuring instrument may furthermore be taken at the remote measuring station as well as at the indicating instrument at the receiving station, because the pointer of the measuring instrument is not hindered in taking up its indicating position.

as it is not turned back into the zero position. If the transmitter measuring instrument is able to deflect from the zero position towards both sides, for instance if it is a wattmeter instrument which apart from the value also indicates the direction of an energy flux the direction of the deflection of its pointer may also be reported to the receiving station and be indicated there. For this purpose the transmitter instrument 5 may influence one bridge resistance in such a manner that by its pointer standing in the zero position it connects a mean resistance value into circuit which is increased or reduced by the deflection of the pointer towards the 10 right or the left. In the same way the pointer of the receiving instrument stands in the center of its scale when the transmitter instrument measures the measuring value "zero" and by deflection towards the left or the right from the 15 central position the direction of the deflection of the pointer of the transmitter instrument is also indicated at the receiving station.

The bridge connection also offers the possibility of combining a plurality of transmitter influences 25 in such a manner that the resistance to be connected in one branch for setting up the balance of the bridge balance is proportional to the product, the quotient or the difference of the measuring values operative on the transmitter side. The 30 square value or the square root value of a transmitter value or the sum of a plurality of transmitter values may also be transmitted. For the transmission of a product, for instance of a current and a voltage, no product measuring apparatus is thus necessary nor is a special instrument necessary for the transmission of an effective or wattless output sum which forms the sum at the measuring station. The transmission of the ratio of two values, such as the real and the 35 apparent output, of steam consumption and electrical output or of direct and alternating current output of a converter, which may be of importance for the supervision of a remote substation of an energy supply system is according to our 40 invention possible without the use of a quotient instrument.

If there exist a plurality of machine units for the generation of electrical energy the transmission of the total output or the total current or 45 the like may be carried out in any other suitable manner than by letting the wattmeter of each machine act on the bridge resistance, and the indication of any preferred instrument measuring the sum of the outputs or currents may according to our invention be transmitted to the receiver station. The instrument which forms 50 the sum of outputs may, in known manner, be a voltmeter if by the values to be added meters are driven in which electromotoric forces proportional to the value of the meter speed are generated the total voltage of which is measured by the voltmeter. The adding up of the individual outputs may, however, also take place in such a way that meters are connected to the generators 55 which during their revolution close contacts the frequency of which in time unit is proportional to the speed of the meter. If the making of the various contacts cause equal current impulses the sum current may be measured by a damped 60 measuring instrument. In this way there is obtained the total effective or wattless output or output of current of the generators. If a plurality of measured values have to be transmitted an order is preferably transmitted from the receiving station which states which measuring

value is transmitted. At the measuring station an instrument is chosen and its drop bow drops on the pointer, the indicating instrument is selected at the receiving station. The compensation of the bridge may be carried out in regular 5 intervals by a clockwork.

This part of our invention will be better understood by reference to Fig. 7 of the drawings. In this figure 710 is the pointer and 716 the drop bow of the transmitter measuring instrument. When the drop bow 716 pulls the pointer down it makes contact on a bridge resistance 717. The remaining bridge resistances are 40 and 50 and 60, 70, 80, 90, 100. The bridge is fed from a battery 711. In the diagonal of the bridge is 15 connected a polarized quickly responding relay 712. The magnitude of the portion of the resistance 717 connected in the bridge will of course depend upon where the pointer 710 touches the resistance. If the bridge balance is disturbed the 20 polarized relay 712 responds and places its armature 713 against either a contact 714 or a stop 715. The disturbed bridge balance may be restored by short circuiting suitable resistances of the individual resistances 60-100 by means of the short 25 circuiting contacts 761, 771, 781, 791 and 701. The short circuiting contacts stand each by itself under the control of a relay 762, 772, 782, 792 or 702, respectively, which in succession are connected in circuit by a contact device 720. The 30 contact device 720 is identical with that shown in Fig. 3. It is provided with two conducting rings 721 and 722 mounted on an insulating base plate 723. The ring 722 is equipped with a vane 724 adjacent to a gap 725. The ring 721 is entirely 35 closed and possesses a vane 726 which projects into the gap 725 of the other ring 722. Upon the insulating disc 723 or the conducting rings 721 and 722 respectively slide contacts, the contacts 727 and 728 or 729 and 730, 731 and 732, 733 and 40 734, 735 and 736 belong to the exciter circuits of the relays 762, 772, 782, 792 or 702 respectively. On the ring 721 also slides a contact 737 and on the ring 722 a contact 738. The contact 738 is connected to one pole of the battery 39. As soon 45 as vane 724 reaches the contact 727 as the contact device 720 revolves, the relay 762 is first excited. Its exciter circuit starts from the battery 739 and passes across the winding of the relay 762, over contact 727, the contact vane 724, the conducting ring 722, the slide contact 738 back to the battery 739. In the same manner the relays 772, 782, 792 and 702 are also connected in circuit in 50 succession. The connection lasts until the vane 724 has again left the respective sliding contacts. On excitation the relays 762, 772, 782, 792 and 702 close holding contacts 763, 773, 783, 793 and 703. Simultaneously one of the resistances 60-100 in the bridge connection is each time short 55 circuited by the armatures 761, 771 and so on. In the sequence in which the relays 762-702 are excited the highest resistance 60 is first short circuited, then the next lower one and so on down to the lowest resistance 100. As long as the pointer 710 is not in contact with the resistance 65 717 the resistance in one bridge branch is infinitely great. The balancing current consequently flowing through the bridge diagonal causes the armature 713 of the relay 712 to be 70 drawn against the stop 715.

The contact device 720 is in any desired manner not shown in the drawings connected with the drop bow 716 in such a way that it starts revolving as soon as the drop bow is pulled down. 75

As already described, relay 762 is then first excited and short circuits the highest of the individual resistances 60-700 by means of the armature 761. In case the total value of the resistances 70-700 remaining in the bridge is still too great to restore the bridge balance a current of such direction flows through the polarized relay 712 that the armature 713 closes the contact 714. This has the effect that the relay 762 which has at its armature 763 prepared a holding circuit for itself remains excited even after the contact vane 724 has left the slide contact 727. The holding circuit for the relay 762 passes from battery 739 across the winding of the relay 162, over the relay contact 763, the sliding contact 728, the contact vane 726 of the conducting ring 721, over the armature 713 and the closed contact 714 to the battery 739. During the further advance of the contact device 720 the contact vane 726 passes beyond the sliding contact 728 and instead of it the other end of the slotted conducting ring 722 connected to the same battery pole passes under the sliding contact 728. Relay 762 thus remains connected in circuit. Immediately afterwards the same process is repeated at the relay 772 which is again first excited across the contact vane 724 and in case relay 712 keeps the contact 713, 714 still closed after the short-circuiting of the individual resistance 70, remains excited across the contact vane 726 and its holding contact 773 until the sliding contact 730 in the holding circuit of this relay passes on to the contact ring 722 during the advance of the contact device 720. As was described for relays 762 and 772 or the bridge resistances 60 and 70 all the resistances 60-700 are temporarily short-circuited and according to whether the polarized relay in the diagonal branch of the bridge determines that too few or too many of the individual resistances are connected in circuit the respective relays remain excited by a holding circuit or they drop off after the temporary excitation.

Each of the relays 762, 772, 782, 792 and 702 controls a third contact 764, 774, 784, 794 and 704 the circuit of which is shown completely only for the relay 702 and the contact 704, in order not to obscure the drawings. The disc 723 of the contact device 720 is mounted upon a shaft 740 upon which is also secured the contact arm 751 of a second contact device 750. The contact arm 751 sweeps across a number of contacts 752, 753, 754, 755 and 756 the number of which depends on the number of relays 762, 772 and so on. The switching in of the relays 762-702 takes place along one portion of a revolution of the shaft 740, during the other portion of the revolution current impulses are sent across the long distance line F to the receiving station by the contact arm 751 and the contacts 752-756. As shown for the relay 702, the relay contacts 764, 774, 784, 794 and 704 close across the contacts 752-756 and the contact arm 751 and the remote line F a circuit to the receiving station across which current impulses are sent from a battery 758. At the receiving station there is provided a receiving equipment operating in synchronism with the contacts 751 which, according to which of the relay contacts 764, 774, 784, 794 and 704 are closed, effect the excitation of corresponding reception members. The start may, particularly if there exist a plurality of measuring stations the measuring results of which are to be reported, be preferably controlled from a point from which emanates also the change over of the bridge connection to the various measuring points, for instance

from a contact device 742 which controls the change over of the measuring stations as well as the operation of the drop bows and the contact devices for the dispatch of the impulses.

The system described for the transmission of measuring values by impulse combinations may with advantage also be used for the synchronizing of interconnected sources of alternating current as will be explained with reference to Fig. 8 of the drawings. In this figure the phases of the alternating current sources to be interconnected are marked by the reference letters U, V, W and u, v, w. Between the line ends U and u, V and v, W and w there must exist no difference of potential in the movement of joining the networks. One or a plurality of voltmeters may thus be built into the described device for remote measuring as transmitter measuring instruments. The indication of these measuring instruments is then reported to the main station and indicated by a receiving instrument. Since, however, the voltages between the line ends to be connected are constantly changing an extraordinarily high transmitting speed is necessary. For this reason it is preferable to indicate at the receiving station only when the frequencies of the networks to be connected have come close together. For this purpose zero voltage relays 810, 820, 830 are used which by their dropping armatures 811, 821, 831 connect definite but differing resistances 812, 822, 832 in the bridge connection. The bridge connection in the illustration also contains the resistances 851 and 852 and the individual resistances 860, 870, 880, 890, 800. In one bridge diagonal is located one source of current 840, in the other again a polarized relay 841 the armature of which places itself in one position against the stop 842 and in the other position against a contact 843. The circuits starting from the contact 843 correspond with Fig. 7. When the frequencies of the alternating current differ only slightly from one another the potentials between the corresponding line ends U and u, V and v, W and w disappear in succession. In consequence thereof the relays 810, 820, 830 drop in slow succession their armatures 811, 821, 831. In this way the fourth bridge branch receives once the resistance value of the resistance 812, another time that of the resistance 822 and again that of the resistance 832. In correspondence therewith the bridge balance must be restored again in each case by a different combination of the individual resistances 860, 870, 880, 890 and 800. Across the contact device 850 there is at the receiving station reported again which of the individual resistances 860, 870, 880, 890 and 800 are connected in circuit. Before the interconnection of the two alternating current sources can take place all the zero voltage relays 810, 820 and 830 must have dropped their armatures. The resistance of the one bridge branch is then equal to the value of the parallel connection of the resistances 812, 822 and 832 which are so stepped that there are no two combinations of these resistances which, when connected in parallel, give the same total resistance. The receiving equipment may control a rotary field indicator which indicates whether the alternating current machine runs too quickly or too slowly but a usual three-lamp connection may be controlled in which the lamps light up in a certain cycle. Instead of the individual resistances 860, 870, 880, 890 and 800 there may, if the problem is to connect by remote indication the correct moment for connecting

two alternating current sources, be used three equal resistances equal to the resistances 810, 820 and 830. The bridge connection may then be abandoned altogether. The relays 810, 820, 5 830 then directly control the impulse combination. By means of any desired change-over device the same bridge connection may be selectively used for the synchronization of a plurality of generators to be synchronized. After the synchronization the bridge connection may be changed over to a measuring instrument which measures the output of the substation, for instance. The changing over may, as indicated be effected by a change over switch 841 which is 10 operated by a relay 846 likewise remotely controlled by a combination of impulses.

The arrangement may be such that at each substation the compensation of the bridge connection is effected anew at regular intervals by 20 a clockwork, for instance. The order for starting the contact devices at the main station and substation is preferably given from the substation. The same bridge connection may there in succession cooperate with a plurality of measuring instruments. The changing over may, for 25 instance, be carried out by a distributor coupled with the contact equipment. The various procedures of the selection of a measuring instrument and the transmission of a measured result 30 may preferably be so connected that while from the main station a substation and a measuring instrument at this station are selected, the compensation takes place at another station which is then transmitted when the impulses for the 35 selection dispatched from the main station are finished. It is an advantage of the mode of transmission described that the transmission is independent of the resistance of the transmission line as long as the arriving impulses suffice at all 40 for the excitation of the relays.

By the same instruments by which an indicating instrument for measured values is adjusted it is also possible to adjust from a transmitting station any other adjustable member at the receiving station. In a control station position indicators may thus be arranged which indicate the 45 positions of switches located at the transmitting station. Conversely the control station may become the transmitting station by, for instance, 50 reversing a switch a corresponding adjustment of a line switch being effected at the remote receiving station. The apparatus illustrated in Fig. 5 may be used for operating the position indicator as well as for the remote control of 55 switches. The selection of a switch or a position indicator may be effected in the same manner as the selection of the measuring instrument V (Fig. 5). The relay R will then control the 60 position indicator or the operating coil of a line switch. The number of the orders possible or of the position indicators becomes still greater if the 65 control relays or the relays of the position indicators are so combined in groups that they take the place of the relays 61, 62, 63 which serve 70 for the adjustment of a measuring instrument. The relays 61, 62, 63 in Fig. 5 may, for instance, control certain movable members which belong to a group to be selected by the relay R. Reports of switch positions and remote control of 75 switches and the like are in this mode of transmission independent of the resistance of the transmission line as long as the arriving impulses suffice at all for the excitation of the relays.

It is also an important advantage of our invention that all the transmitting means known

in the art of telegraphy may be used. The impulses may also be transmitted without wires, either by space waves or line-directed waves, for instance across telephone lines, particularly telephone lines in high-tension networks. The 5 impulses may also be transmitted across telephone lines and telegraph lines as well known in the underposed or sound frequency telegraphy.

In some cases it is of value of add a number of measured values for instance, if it is desired 10 to control at a central control station the entire output of a plurality of cooperating electricity stations. The added value may then be easily indicated by providing an indicating instrument which is operated by the action of the impulses 15 sent out from the various power stations or measuring stations. If for the indication of the service values measured at the individual measuring stations electrical measuring instruments are used which set themselves according to the re- 20 sistance or conducting values of the arriving values, the device indicating the value of the sum may be a similar instrument which responds to the sum of these resistances or conducting values, i. e. a voltmeter or an ammeter of considerable 25 measuring range.

If only two measuring values are to be transmitted their sum or difference may at the starting station be formed, for instance, so that one measured value adjusts the pointer and the other 30 a movable scale of the same indicating instrument in the same or opposite direction of motion. When using product meters or quotient meters of known construction it is also possible to form at the receiving station the product or 35 the quotient of two measured values. If the two transmitted service values correspond with the voltage and the current of an alternating current circuit the product indicated is equal to the apparent output of the respective alternating current circuit in volt-amperes and the quotient 40 equal to the impedance of this circuit.

Various modifications and changes may be made without departing from the spirit and the scope of the invention, and we desire, therefore, 45 that only such limitations shall be placed thereon as are imposed by the prior art.

We claim as our invention:

1. In an apparatus for transmitting the condition of a measuring instrument which is operated by a measuring torque on a pivoted part thereof, in combination, a plurality of comparison elements for exerting a plurality of counter-torques on said pivoted part, said elements being graduated in power so that each of the counter- 50 torques produced by them will be of a magnitude differing from the magnitudes of the other counter-torques, means for comparing first the element exerting the greatest counter-torque and then successively the others, in the order of the 55 magnitude of their counter-torques, with the measuring torque acting on said pivoted part, means for eliminating successively that counter-torque or those counter-torques, from the largest down, which either alone or by addition to some 60 larger retained counter-torque exceed said measuring torque, a remote receiving apparatus including a plurality of elements bearing the same magnitude relation to each other as the counter-torques exerted by said comparison elements, and means for transmitting to said remote receiving apparatus, by impulse combinations acting on said elements of the receiving apparatus, the value of that counter-torque, or 65 the sum of the values of those successively com- 70

pared counter-torques, which either equals the said measuring torque or, while smaller than such measuring torque, constitutes the closest approximation thereto.

- 5 2. In an apparatus for transmitting the indications of a measuring instrument, in combination, a variable resistance, mechanism operative to vary the magnitude of said resistance in dependence upon the indication of the measuring instrument, a second resistance comprising a plurality of comparison resistance units each of a magnitude differing from the magnitudes of the other comparison resistance units, means for comparing first the largest of said resistance units 10 and then successively the others, in the order of their magnitudes, with the first-mentioned variable resistance, means for eliminating successively that comparison resistance unit or those comparison resistance units, from the largest 15 down, which either alone or by addition to some larger retained unit exceed said first-mentioned variable resistance, a remote receiving apparatus including a plurality of elements bearing the same magnitude relation to each other as said comparison resistance units, means for transmitting the magnitudes of the other comparison resistance units to said receiving apparatus by impulse combinations acting on said elements, and an indicating device adjustable by said receiving 20 apparatus in accordance with the message received.

3. In an apparatus for transmitting the indications of a measuring instrument, in combination, a variable resistance, mechanism operative to vary the magnitude of said resistance in dependence upon the indication of the measuring instrument, a second resistance comprising a plurality of comparison resistance units each of a magnitude differing from the magnitudes of the other comparison resistance units, means for comparing first the largest of said resistance units and then successively the others, in the order of their magnitudes, with the first-mentioned variable resistance, said means comprising a contact 35 device, relays controlled by said device, holding circuits for said relays, said relays arranged to select successively the comparison resistance units corresponding to said first-mentioned variable resistance, said first and second resistances being each arranged in a branch of a bridge connection, a bridge relay in a diagonal of the bridge operable upon excitation in one direction to close a holding circuit, and, upon excitation in the opposite direction, to cause such holding circuit to be 40 opened to eliminate the particular comparison resistance unit associated with such holding circuit, a remote receiving apparatus including a plurality of elements bearing the same magnitude relation to each other as said comparison resistance units, mechanism for transmitting to said remote receiving apparatus impulse combinations acting on said elements in correspondence with the comparison resistance units required to match accurately or approximately 45 the first-mentioned variable resistance, and an indicator actuated in accordance with the action of said impulse combinations on said elements.

4. In an apparatus for transmitting the condition of a movable member whose condition can be expressed as a measurable value, in combination, a plurality of comparison elements all of the same character but each of a magnitude differing from the magnitudes of the other comparison elements, means for comparing first the largest of 50 said elements and then successively the others, in

the order of their magnitude, with the condition of said movable member, means for producing impulse combinations in dependence upon the result of such comparison, means for sending an auxiliary impulse of a different kind for every impulse of the impulse combination, a receiving apparatus including a plurality of elements bearing the same magnitude relation to each other as said comparison elements, means for taking up the impulse combinations and the auxiliary impulses, and a stop device for arresting the operation of the receiving apparatus when the reception of the impulse combinations or of the auxiliary impulses is disturbed. 5

5. In an apparatus for transmitting the condition of a movable member whose condition can be expressed as a measurable value, in combination, a plurality of comparison elements all of the same character and each of a magnitude different from the magnitudes of the other elements, means for comparing first the largest of said elements and then successively the others, in the order of their magnitude, with the condition of the movable member, means for producing electric impulse combinations in dependence upon the result of said comparison, means for sending an auxiliary impulse of opposite direction for each impulse of an impulse combination, a receiving apparatus including a plurality of elements bearing the same magnitude relation to each other as said comparison elements, means for taking up the impulse combinations and the auxiliary impulses, and a stop device for arresting the operation of the receiving apparatus when the reception of the impulse combinations or of the auxiliary impulses is disturbed. 15 20 25

6. In an apparatus for transmitting the indications of a measuring instrument, in combination, a plurality of comparison elements all of the same character and each of a magnitude different from the magnitudes of the other elements, means operative periodically for comparing first the largest of said elements and then successively the others, in the order of their magnitude, with the indication to be transmitted, a remote receiving apparatus including a plurality of elements bearing the same magnitude relation to each other as said comparison elements, means for establishing a transmitting relation between the comparison element or elements which or the sum of which corresponds exactly or approximately to the indication to be transmitted, and the receiving apparatus element or elements corresponding in magnitude to such comparison element or elements, and means for transmitting an indication of the magnitude of such comparison element or elements to the corresponding receiving apparatus element or elements by means of impulse combinations. 40 45 50 55

7. In an apparatus for transmitting values, in combination, transmission apparatus including a plurality of comparison elements and means for comparing the value to be transmitted successively with the values of a plurality of said comparison elements until a value or group of values is found which equals or closely approximates the value to be transmitted, a remote receiving apparatus including a plurality of elements bearing the same relation to each other as the values of said comparison elements, and means for communicating to said remote receiving apparatus, by impulse combinations acting on its elements, that value or group of values determined at the transmission apparatus as equaling or closely approximating the value to be transmitted. 60 65 70 75 75

8. In an apparatus for transmitting values, in combination, transmission apparatus including a plurality of comparison elements each of a value differing from those of the other elements and means for comparing the value to be transmitted, successively with the element having the largest value and then in sequence with the others, until a value or group of values is found which equals or closely approximates the value to be transmitted, a remote receiving apparatus including a plurality of elements bearing the same relation to each other as the values of said comparison elements, and means for communicating to said remote receiving apparatus, by impulse combinations acting on its elements, that value or group of values determined at the transmission apparatus as equaling or closely approximating the value to be transmitted.
9. In an apparatus for transmitting values, in combination, transmission apparatus including a plurality of comparison elements each of a value differing from those of the other elements, means for comparing the value to be transmitted, successively with the element having the largest value and then in sequence with the others, means for eliminating successively that comparison element or those comparison elements, from the largest down, which either alone or by addition to some previously compared element, exceeds or exceed the value to be transmitted, until a value or group of values is found which equals or closely approximates the value to be transmitted, a remote receiving apparatus including a plurality of elements bearing the same relation to each other as the values of the said comparison elements, and means for communicating to said remote receiving apparatus, by impulse combinations acting on its elements, that value or group of values determined at the transmission apparatus as equaling or closely approximating the value to be transmitted.
10. In an apparatus for transmitting the condition of a measuring instrument which is operated by a measuring torque on a pivoted part thereof, in combination, a plurality of comparison elements for exerting a plurality of counter-torques on said pivoted part, means for comparing first the counter-torque exerted by one of said elements and then successively those exerted by the other comparison elements, with the measuring torque acting on said pivoted part, means for eliminating successively that counter-torque or those counter-torques which either alone or added to the counter-torque of some previously compared element exceed said measuring torque, until a value or group of values represented by such counter-torques is found which equals or closely approximates said measuring torque, a remote receiving apparatus including a plurality of elements bearing the same relation to each other as the values of the counter-torques exerted by said comparison elements, and means for communicating to said remote receiving apparatus, by impulse combinations acting on its elements, that value or group of values determined at the transmission apparatus as equaling or closely approximating the said measuring torque.
11. In an apparatus for transmitting the indications of a measuring instrument, in combination, a variable resistance, mechanism operative to vary the magnitude of said resistance in dependence upon the indication of the measuring instrument, a second resistance comprising a plurality of comparison resistance units, means for comparing first one of said resistance units and then the others with the first-mentioned variable resistance, means for eliminating successively that comparison resistance unit or those units which either alone or added to some previously compared unit exceed the value of said variable resistance corresponding to the indication of the measuring instrument, until a value or group of values represented by said units is found which equals or closely approximates that value of said variable resistance which corresponds to the indication of the measuring instrument, a remote receiving apparatus including a plurality of elements bearing the same relation to each other as the values of said comparison resistance units, and means for communicating to said remote receiving apparatus, by impulse combinations acting on its elements, that value or group of values determined at the transmission apparatus as equaling or closely approximating that value of said first-mentioned variable resistance which corresponds to the indication of the measuring instrument.
